CLAIM

The ornamental design for a detachable hand grip tool, as shown and described.

DESCRIPTION

FIG. 1 is a plan view of a detachable hand grip tool with the parts shown separated for clarity of illustration only; FIG. 2 is an end view of the tool shown in FIG. 1; FIG. 3 is a side view of the tool shown in FIGS. 1 and 2; FIG. 4 is a perspective view of the parts of the tool shown in FIGS. 1 and 3 aligned prior to joining; and, FIG. 5 is a perspective view of the tool with the parts joined. The undisclosed views of the tool are identical in appearance to those views shown in FIGS. 1-5.
